TREATMENT OF YARNS

Robert Wighton Moncrieff and George Wilson
Harrison, Spondon, near Derby, England, as-
signors to Celanese Corporation of America,
a corporation of Delaware

Application February 20, 1934, Serial No. 712,110
In Great Britain March 10, 1933

1 Claim. (Cl. 28—26)

This invention relates to the treatment of yarns, and particularly to operations involving the simultaneous treatment of a plurality of yarns, e. g. in the form of a warp or sheet.

Where a plurality of yarns have been disposed in warp form chiefly for convenience in handling and for uniformity of treatment of such yarns, it is generally desirable, after such treatment, to collect the yarns on a plurality of bobbins. The yarns may then be submitted to further treatments in which the warp formation would be less convenient, and may be employed as individual yarns in further textile operations.

According to the present invention several yarns, which have been treated simultaneously, are assembled as a narrow ribbon, which is wound on a single package, and is subsequently unwound, and divided during unwinding into a number of ends, such ends being rewound separately on a corresponding number of packages. The yarns of the group having been wound together as a ribbon which is traversed on to a single package, they may be submitted to further treatment on the package as though they were a single yarn. By reason of their ribbon form however, they may be separated subsequently and again dealt with as individual yarns, being, for example, separately twisted, or doubled together in any desired combination with one another.

Where a very large number of yarns have been treated in the form of a warp or sheet, they may be collected in this manner on a plurality of packages, whose number however, is far less than would be necessary if each yarn were to be wound on a separate bobbin, and the apparatus required is correspondingly smaller and less costly. At the same time the multiple end packages offer considerable advantage in enabling any desired number up to the total number of ends on each package to be taken together and separated from the whole package as a single thread.

The importance of winding the several yarns of each group of yarns or multiple yarn in the form of a ribbon, is most marked when the yarns being wound are of low twist, and particularly when they consist of continuous filaments lightly twisted together. In such a case slight local twist between the yarns, or laying of one end over another might easily bring about entanglement of the ends. By guiding the several ends of yarn to be simultaneously wound into ribbon form however, and winding them on the bobbin in such ribbon form, the ends are laid

side by side on the take-up bobbin and the difficulty arising from overlapping of one end over another is avoided. Consequently, on unwinding the ends separate readily from each other and re-winding can proceed with little danger of interruption.

Care should be taken in traversing the ribbon on to the take-up package to avoid any tendency to undue piling of the yarn at the ends of the traverse, since in this way some overlapping of the several ends in the ribbon might arise.

The invention is of particular advantage in the collection of yarns after they have been stretched in warp form e. g. as described in respect of yarns of cellulose acetate or other cellulose derivative in U. S. application S. No. 602,844 filed 2nd April, 1932. In such a case, the yarns may enter the stretching operation having a certain denier, say 150—200 denier, and may be stretched, say to five or six times their original length, the stretched yarns being collected as groups on separate bobbins, each group, or multiple yarn, being of any desired denier, e. g. of a denier approximately to the 150—200 of the original yarns. Since, moreover, the twist in the initial yarn has been largely lost on account of the extension imparted to the yarn, it is almost always necessary to re-twist the stretched yarn, so that the collection of the yarn as multiple-end packages instead of as packages containing single ends of the yarn can be made to yield as many yarns of different final denier as could be obtained by combining yarns from single-end packages without, however, involving any further intermediate operation, and, of course, bringing in the advantages as regards winding and reduction of machine size mentioned above.

Where two or more ends are taken together from the multiple-end on the package, they may be doubled together, as explained below, this operation conveniently taking place continuously with unwinding.

In order to bring the ends into ribbon form the traverse guide is conveniently made in the form of a comb, through the teeth of which the ends are threaded. It is advisable not to have the teeth of the comb too closely spaced, and it is preferred to have a fairly wide spacing, say $\frac{1}{8}$ inch, and to incline the comb in order to bring the ends as close together as is desired in the ribbon. Thus for example the ribbon may be conveniently $\frac{1}{8}$ or $\frac{3}{16}$ inch wide in a ribbon containing 5 or 6 ends for simultaneous winding.

By way of example the invention will now be

described in greater detail with reference to the accompanying drawing in which:—

Figures 1, 2 and 3 are a front elevation, a side elevation and a plan view respectively of winding mechanism suitable for carrying out the invention, and

Figures 4 and 5 are illustrations of two methods of unwinding a package which has been wound in the manner according to the invention.

10 With reference to Figures 1-3, six separate threads 6 are led from a stretching apparatus or other suitable source of supply to a bobbin 7 which is rotated by means of a driving drum 8 (Figure 2) contacting with the yarn on the surface of the package so as to give constant speed yarn take-up. The form of apparatus described in U. S. application S. No. 705,864 filed 9th January, 1934, may be adopted in the driving of the drum 8, so as to enable the yarns to be wound 15 under controlled tension, and to allow any slack occurring in starting to be readily taken up.

On their way to the package 7, the threads 6 pass between the teeth 9 of a comb or reed, indicated generally at 10, the comb 10 being mounted 25 on a reciprocating traverse bar 11 which traverses the threads on to the package 7. The comb 10 in this instance comprises seven teeth 9 which are held between two rods of stainless metal 12, the upper ends of the teeth being 30 covered by a bent sheet metal cover 13. The rods 12 provide a smooth surface in contact with which the threads 6 may pass without damage. The teeth 9 may themselves be of similar material.

35 The comb or reed 10 collects the threads 6 together in the form of a flat ribbon 14, the comb 10 being set at an angle to the ribbon 14 so that while the teeth 9 are not spaced unduly closely together, the ribbon 14 is a narrow one.

40 The comb 10 is carried upon a rod 15 held in a bracket 16 by means of a butterfly nut 17 which may be slackened to permit the angle of the comb 10 to the ribbon 14 to be adjusted. The bracket 16 is carried upon an adjusting screw 18 having a 45 milled head 19 and a milled nut 20 which permits the precise position of the comb and the traverse bar 11 to be accurately adjusted at the beginning of the winding operation. By these means the six threads 6 are wound on the bobbin 7, in the 50 form of a narrow ribbon, and are prevented from lying over the top of one another in such a manner as to hinder the subsequent unwinding of the threads.

The threads may be unwound from the package and twisted separately or doubled together in any desired manner. Thus, in Figure 4 a package 21 is shown on which are wound four threads 22 in the form of a ribbon 23. The ribbon 23 is drawn from the package and the four threads 22 of which it consists, are separated by passing them through a guide comb 24 having five teeth 25. The threads 22 are then led separately to four thread guides 26, round feed rollers 27, and 10 thence to the balloon guides 28 of four separate ring spinning devices 29 which are driven in pairs by means of belts 30. By these means the four threads are separately twisted and wound on the packages 31.

15 In Figure 5 a package 32 is shown on which a ribbon 33 consisting of six threads is wound. The threads may, for example, be of 25-30 denier each, having been produced by stretching yarns initially of 125-150 denier to five times their 20 length. The threads are passed through a separating comb 34 and then conducted as two assemblies 35 of three threads each through guides 36, round feed rollers 37 and thence to the balloon guides 38 of two ring spinning devices 39. The 25 feed rollers 37 rotate all at the same speed, so that the ribbon 33 is uniformly drawn from the bobbin 32. By means of the device 37 the three threads of each assembly 35 are doubled together into a single thread and collected on the packages 40. Similarly, the ribbon 33 might have been split into three assemblies of two threads each, or into two assemblies, one of four threads and one of two, or with any other desired combination.

35 What we claim and desire to secure by Letters Patent is:—

An apparatus for the winding of a group of yarns concomitantly with their simultaneous treatment on to a single package while they are 40 in the form of a ribbon, said apparatus comprising a package support, means for rotating said support about its axis, a comb for guiding the yarns in the form of a narrow ribbon to said package support, said comb being disposed at an angle 45 to the axis of the package support so as to produce a ribbon which is narrower than the width of the comb, and means for traversing said comb in a direction parallel to the axis of the package support.
